(57) **CLAIM**

The ornamental design for a wave pattern concrete masonry unit, as shown and described.

DESCRIPTION

FIG. 1 is a perspective front view of a wave pattern concrete masonry unit showing my design;

FIG. 2 is a front view of the wave pattern concrete masonry unit of FIG. 1;

FIG. 3 is a right side view of the wave pattern concrete masonry unit of FIG. 1;

FIG. 4 is a left side view of the wave pattern concrete masonry unit of FIG. 1;

FIG. 5 is a bottom plan view of the wave pattern concrete masonry unit of FIG. 1;

FIG. 6 is a top plan view of the wave pattern concrete masonry unit of FIG. 1; and,

FIG. 7 is a front view of the wave pattern concrete masonry unit of FIG. 1 assembled with other wave pattern concrete masonry units in a segment of a block wall so as to display a wave pattern.

The broken lines immediately adjacent the shaded areas in FIGS. 1 and 3-6 represent the bounds of the claim, the broken line showing of the like concrete masonry units in FIG. 7 and all other broken lines are for illustrative purposes only. None of the broken lines form a part of the claimed design.
